UNITED STATES PATENT OFFICE

100,550

DESIGN FOR A SETTEE FRAME OR SIMILAR ARTICLE

John Di Martino, Brooklyn, N. Y.

Application May 26, 1936, Serial No. 62,836

Term of patent 14 years

To all whom it may concern:

Be it known, that I, John Di Martino, a citizen of the United States and resident of Brooklyn, in the county of Kings and State of New York, have invented a new, original, and ornamental Design for a Settee Frame or Similar Article, of which the following is a specification, reference being had to accompanying drawing, forming a part thereof, in which:

Figure 1 is a front perspective view of the settee frame, showing my design, it being understood that the frieze, which is partially shown, extends

completely along the front panel of the settee; and

Figure 2 is a fragmentary, enlarged detail front elevational view of said frieze.

The dominant feature of my design consists in the frieze.

I claim:

The ornamental design for a settee frame or similar article, as shown and described.

Signed at New York, in the Borough of Manhattan, county and State of New York this 14th day of May 1936.

JOHN DI MARTINO,
